UNITED STATES PATENT OFFICE.

AUGUST SCHUBERT, OF ONEIDA, NEW YORK.

SPRING-VEHICLE.

SPECIFICATION forming part of Letters Patent No. 378,180, dated February 21, 1888.

Application filed September 7, 1887. Serial No. 249,007. (No model.)

To all whom it may concern:

Be it known that I, AUGUST SCHUBERT, of Oneida, in the county of Madison, in the State of New York, have invented new and useful 5 Improvements in Spring-Vehicles, of which the following, taken in connection with the accompanying drawings, is a full, clear, and exact description.

This invention relates to the class of spring-gears usually designated "duplex" spring, in 10 which two springs are arranged respectively at opposite sides of and parallel with the axle.

The invention consists in supporting the springs on the axle by means of spring-arms secured to the end portions of the axle and standing lengthwise thereof and couplings connecting the ends of the springs to the vibratory ends of the spring-arms. Said combination and arrangement of parts constitute a duplex 20 spring-gear which is compact, simple, and comparatively inexpensive, and affords increased elasticity without inducing lateral swaying of the body of the vehicle.

The invention is fully illustrated in the annexed drawings, in which Figure 1 is a front elevation of a spring-gear embodying my improvements. Fig. 2 is a top plan view of the same. Fig. 3 is a transverse section on line $x-x$, Fig. 2. Fig. 4 is a vertical longitudinal section on line $y-y$, Fig. 2. Fig. 5 is a detached top plan view of one of the spring-arms. Fig. 6 is a side elevation of a modification of the spring-arm, and Fig. 7 is an end view showing a modification of the spring-coupling.

Similar letters of reference indicate corresponding parts.

A represents the axle, which is preferably formed with the downwardly-deflected portion A' A'. On the end portions of this axle I 40 mount spring-arms C C, which stand in the direction of the length of the axle and are preferably secured to the top of the downwardly-deflected portions A' A' of the axle by clips e, embracing the said axle portions and super- 45 incumbent attaching ends of the spring-arms C C, as illustrated in Fig. 1 of the drawings, the free or vibratory ends of the spring-arms rising outward from the aforesaid portions of the axle. In order to prevent the spring-arm C from slipping longitudinally on the axle, I 50 provide the top of the latter with a recess, b, into which projects either the bolt or head of

the bolt which fastens together the leaves of which the spring-arm is composed, as illustrated in Fig. 4 of the drawings.

The free end of the spring-arm C is formed with a lateral flare, c, and with an eye or sleeve, a, across the flare, and on opposite ends of said eye are hung the springs D D, which are arranged at opposite sides of the axle and terminate with the usual eyes for the reception of the bolt by which they are coupled to the two spring-arms C C. The connection of the springs D D with the spring-arm C, I prefer to make by placing the eyes of the springs D D in range with the eye a of the spring-arm and close to the ends thereof and extending the coupling-bolt through the three eyes, as represented in Fig. 3 of the drawings, and on heavy vehicles I reinforce the said coupling by mounting on top of the eye a a saddle, h, which projects over the eyes of the springs D D and terminates with perforated ears i i at the outsides of the spring-eyes and receives through said ears the ends of the bolt which couples the springs D D to the spring-arm, as illustrated in Fig. 7 of the drawings. I do not, however, limit myself to any specific coupling devices, as the same admits of many modifications.

It will be observed that when the spring-arms C C are arranged on the downwardly-deflected portions A' A' of the axle, as shown in Fig. 1 of the drawings, the spring-arms, when depressed, are brought to bear on the axle nearer the oscillatory ends of the spring arms, and thus the supports of said arms are re-enforced in accordance with the increase of the strain applied to them.

Although I prefer the arrangement of the spring-arms C C, as before described, yet I do not wish to be limited in this respect, inasmuch as it admits of many modifications, one of which is illustrated in Fig. 6 of the drawings, in which the spring-arm C is placed reverse from the position hereinbefore described, and is rigidly mounted on the horizontal end portion of the axle. The springs D D may be connected to this spring-arm in the same manner as shown in Fig. 3 of the drawings.

Having described my invention, what I claim as new, and desire to secure by Letters Patent, is—

1. The combination of the axle A, formed with the downwardly-curved portions A' A',

the spring-arms C C, secured to the top of the axle portions A' A' and rising outward therefrom, and the springs D D at opposite sides of the axle and hung on the outer ends of said 5 spring-arms, substantially as described and shown.

2. In combination with the axle, the spring-arms C C, secured to the end portions of the axle and rising therefrom parallel with the 10 axle and terminating in the lateral flares c, and the springs D D, hung on the flaring ends of the spring-arms, as set forth and shown.

3. In combination with the axle, the spring-arms C C, secured to the top of the end portions of the axle and rising outward therefrom 15 and parallel therewith and terminating in the lateral flares c, and eyes a on said flares, and the springs D D, hung on said eyes, substantially as described and shown.

4. The combination of the axle provided with 20 the recesses b b, the leaf spring-arms C C, mounted on top of the end portions of the axle and rising therefrom lengthwise thereof, the bolts d d, fastening the leaves of the springs and entering the aforesaid recesses, clips e e, 25 fastening the spring-arms to the axle, and the springs D D, hung on the free ends of the spring-arms, substantially as described and shown.

In testimony whereof I have hereunto signed my name, in the presence of two witnesses, at 30 Syracuse, in the county of Onondaga, in the State of New York, this 30th day of August, 1887.

AUGUST SCHUBERT. [L. S.]
